STORM SASH OPERATOR

Per Otto Anderson, Minneapolis, Minn.

Application January 30, 1932. Serial No. 589,850

10 Claims. (Cl. 20—55)

This invention relates to an operator for a storm sash and a window sash, and more particularly to an operator controllable from the interior of the building to which the sashes are attached.

An object of my invention is to provide convenient means controllable from the interior of a building, whereby a storm sash can be opened or closed without the necessity of first opening 10 a window sash to gain access to operating mechanism.

Another object of my invention is to provide operating means of the class described in which the degree of opening is adjustable to various 15 intermediate positions, ranging from the closed position to the position representing the maximum opening provided.

A further object is to provide a sash operator in which means is included for raising and lowering the upper window sash simultaneously with the closing and opening of the storm sash by the 20 operation of a single common control member.

To these ends, generally stated, the invention consists in the novel parts and novel combinations of parts hereinafter defined in the claims and described in the following specification, made in connection with the accompanying drawing, wherein like reference characters refer to the same or similar parts throughout the various 30 views, and, in which,

Fig. 1 is a vertical sectional view taken through a window frame structure and illustrating an embodiment of the invention operatively applied for use, certain of the movable parts being illustrated in one position in full lines and in another 35 position in dotted lines;

Fig. 2 is a horizontal sectional view taken on the line 2—2 of Fig. 1, as indicated by the arrows;

Fig. 3 is a vertical sectional view taken on the 40 line 3—3 of Fig. 2, as indicated by the arrows;

Fig. 4 is a vertical sectional view taken on the line 4—4 of Fig. 1, as indicated by the arrows; and

Fig. 5 is a vertical sectional view taken on the 45 line 5—5 of Fig. 2, as indicated by the arrows.

Referring to the drawing, in a wall W, the exterior surface of which is indicated by Wa and the interior surface of which is indicated by Wb, a window sash frame 6 of conventional form is 50 mounted. In the window sash frame 6, an upper window sash 7 and a lower window sash 8 of conventional form are slidably mounted to permit vertical motion with respect to the sash frame. Outward of the window sashes 7 and 8 is a storm sash 9 pivotally connected at its lower end to sill

10 of sash frame 6 by means of hinges 11. The storm sash may be swung from a closed position shown in full lines Fig. 1 to an open position shown in dotted lines Fig. 1. At the upper end of the storm sash 9, a plate 12, disposed parallel to the plane of the sash and projecting upward beyond the upper end of the storm sash, is attached to the outer surface of the storm sash. A pair of bars 13 are pivotally and removably attached to a lug 14 on the inner face of said plate 12 as by means of a cotter pin 13a running through short vertical slots in the outer ends of the bars 13. The said bars 13 extend in a substantially horizontal direction through a channel-shaped casing in line with apertures 15 in the sash frame 6 to a point beyond the inside surface of the upper portion of the window sash frame. The plate 12 is of such size and proportion as to effectively cover aperture 15 at the outer side of the sash frame 6 when the storm sash 9 is in the closed position. On the underside of each of the two bars 13 are formed rack teeth 16. The inner end of the bars are pivotally attached to an operating lever 17 of arcuate shape, said operating lever having a projecting straight handle portion 17a. The upper end of the operating lever is formed into a ball 18, said ball being retained in pivotal and vertically slidable relation within a vertically disposed guide 19 of C-shape in horizontal cross section, said guide being attached to the interior face Wb of the wall W above the window sash frame 6. An upturned lip 21 of the casing 20 substantially flush with the inner face of the upper member of the window sash frame 6 is adapted to be engaged with the rack teeth 16 of the bars 13. Disposed within the casing 20 is a gear 22 rotatably mounted on a pin 23, said pin lying in a plane parallel to the plane of the sash frame 6 and supported at its ends by the side walls of the casing 20. The gear 22 is engaged with the rack teeth 16 of the bars 13. Above the bars 13 is a pin 24, said pin being supported at its ends by the side walls of the casing 20 and located a suitable distance above the pin 23 to permit a slight upward motion of the bars 13 sufficient to allow disengagement of the rack teeth 16 from the upturned lip 21 of the casing 20 without allowing the rack teeth 16 to be disengaged from the teeth of the gear 22. A vertically disposed rack 25 with inwardly projecting teeth 26 is pivotally attached, as by a pin 27a, at its lower end to a lug 27 which is secured to the upper member of the upper window sash frame 7. The rack 25 is so located that it passes between the two bars 13. The teeth 26 of the rack 25 is engaged with the teeth of the 110

gear 22. A guide surface 28 prevents the rack 25 from being moved outwardly and thus prevents disengagement of the teeth 26 of the rack 25 from the teeth of the gear 22. The outer surface 25a of the rack 25 recedes inwardly at the upper end, as shown in Fig. 1, to facilitate engagement or disengagement of the rack teeth and the teeth of gear 22 when assembling or disassembling the sash operator.

10 An outwardly and downwardly sloping rain shield 29 is attached to the outward surface Wa of the wall W above the window sash frame 6.

Operation

15 Assuming the storm sash 9 to be in closed position indicated by full lines Fig. 1, the operation to open the storm sash to the dotted line position is as follows:—

20 The handle portion 17a of the operating lever 17 is slightly raised to disengage the rack teeth 16 of the bars 13 from the upturned lip 21 of the housing 20. The operating lever 17a is then pushed toward the sash frame 6, thus pushing the upper end of the storm sash 9 outward to the 25 dotted line position Fig. 1. As the operating lever handle 17a is pushed outwardly, the ball-shaped end 18 of the operating lever 17 moves upward in the guide 19.

25 Referring to Fig. 3, as the above described operation is performed, the bars 13 are moved in an outward direction. Since the teeth 16 of the bars 13 are engaged with the teeth of the gear 22, outward motion of the bars 13 will cause clockwise rotation of the gear 22. Since the teeth of the 30 gear 22 are engaged with the teeth 26 of the rack 25, clockwise rotation of the gear 22 will cause downward motion of the rack 25. The rack 25 is attached to the upper window sash 7 and hence the downward motion of the rack 25 results in 35 downward motion or opening of the window sash 7.

40 To close the storm sash 9 and raise the upper window sash 7, the operation consists of slightly raising the handle 17a of the operating lever 17 and pulling the handle inward. The operation of the various parts of the structure are obviously 45 in the direction opposite to that described in connection with the operation of opening the storm sash.

45 The bars 13 can be disengaged from the lug 14 by removing cotter pin 13a when it is desired to remove the storm sash 9 for summer storage. The vertical rack 25 can be disengaged from the 50 lug 27 by removing pin 27a if it is desired to 55 operate the upper window sash 7 independently of the operator while the storm sash is in summer storage.

55 It will be seen that the operator is simple in construction and in operation. It will also be 60 observed that if the lip 21 is eliminated, the storm sash 9 can be readily swung to and from open position merely by operation of the sliding sash 7. The rain shield 29, of course, prevents rain or snow from falling between the storm sash 9 and the lower sliding sash. Although the operator is particularly applicable for use at the top of a window sash frame for opening and closing a storm sash hinged at its lower edge to the sill of the window frame, it will be understood that 65 the operator by slight changes in the construction thereof, could be adapted for use adjacent the bottom of a sash frame for controlling a storm sash pivotally mounted on the sash frame at its upper edge.

70 75 It will, of course, be understood that various

changes may be made in the form, details, arrangement and proportions of the various parts without departing from the scope of the present invention.

What is claimed is:—

1. The combination with a window sash frame and a swinging storm sash, of a storm sash operator comprising a bar pivotally connected to the swinging edge of the storm sash and extending inwardly through the sash frame, a lever pivoted to the inner end of said bar and a guide mounted at the inner side of the sash frame within which said lever is pivotally and slidably mounted.

2. The structure defined in claim 1, said bar having teeth formed in one edge thereof and a member with which any one of said teeth may be engaged, the teeth of said bar being disengagable from said member by moving said bar in a direction away from said member.

3. A storm sash operator comprising, a bar adapted to be pivotally connected to the swinging end of a storm sash to project inwardly through a sash frame, a guide adapted to be mounted at the inner side of the sash frame and a lever pivotally and slidably mounted in said guide and pivotally connected to the inner end of said bar.

4. The combination with a window sash frame, located in the wall of a building, and a storm sash, of a storm sash operator comprising a bar pivotally attached to the swingable end of said wall, an operating lever pivotally attached to the inner end of the bar and formed at one end into a ball, and a guide attached to the inner face of the wall, said ball being retained in pivotal and 110 slidable relation within said guide.

5. The combination with a window sash frame, located in the wall of a building, and a swinging storm sash, of a storm sash operator, comprising a plate secured to the outer surface of the swingable sash and projecting beyond said swingable end, and a bar pivotally attached to the projecting portion of said plate, said wall having an aperture through which said bar extends to the inner side of the wall, the outer end of said 120 aperture being covered by said plate when the storm sash is in its closed position.

6. The combination with a window sash frame, a sliding sash and a swinging sash, of a sash operator comprising a rack pivoted to the swinging 125 end of said swinging sash and running through said sash frame to the inner side thereof, a gear mounted within said sash frame with which said rack engages, a rack connected to said sliding sash and engaging said gear, guide means for 130 preventing disengagement of said last mentioned rack from said gear and means for moving said first mentioned rack inwardly and outwardly.

7. The combination with a window sash frame, a sliding sash and a swinging sash, of a bar 135 pivoted to the end of said swinging sash and projecting inwardly through said sash frame adjacent one end thereof, a gear mounted in said sash frame and engaging said rack, a rack connected with said sliding sash and also engaging said gear, and guide means for said two racks preventing disengagement of said racks from said gear whereby as one of said sashes is moved, the other of said sashes will also be moved therewith.

8. The combination with a window sash frame and a swinging storm sash, of a storm sash operator comprising a bar pivotally connected to the swinging edge of the storm sash and extending inwardly through the sash frame, said bar hav-

ing teeth formed in one edge thereof, and a member with which any one of said teeth may be engaged, the teeth of said bar being disengageable from said member by moving said bar in a 5 direction away from said member.

9. The combination with a window sash frame and a sliding sash of a sash operator comprising a rack running through said sash frame to the inner side thereof, a gear mounted within said 10 sash frame with which said rack engages, a rack connected to said sliding sash and engaging said gear, guide means for preventing disengagement of said racks from said gear, and means for moving said first mentioned rack inwardly 15 and outwardly.

10. The combination with a window sash frame and a swinging storm sash, of a storm sash operator comprising a bar pivotally connected to the swinging edge of the storm sash and extending inwardly through the sash frame, and a lever 80 pivotally connected at one point to the inner portion of said bar and at another point to the inner side of said frame, said bar having teeth formed in one edge thereof and a member with which any one of said teeth may be engaged, 85 the teeth of said bar being disengageable from said member by moving said bar in a direction away from said member.
